Patented Sept. 13, 1921.

Inventor

Harry C. Adam

UNITED STATES PATENT OFFICE.

HARRY C. ADAM, OF ST. LOUIS, MISSOURI.

DESIGN FOR A WALL-PLATE FOR LIGHTING-FIXTURES.

58,985.

Specification for Design.

Patented Sept. 13, 1921.

Application filed January 14, 1921. Serial No. 437,362. Term of patent 14 years.

To all whom it may concern:

Be it known that I, HARRY C. ADAM, a citizen of the United States, residing at St. Louis, Missouri, have invented a certain new, original, and ornamental Design for a Wall-Plate for Lighting-Fixtures, of which the following is a specification, reference being had to the accompanying drawing, forming a part thereof.

The drawing is a side elevational view of my new ornamental design for a wall plate for lighting fixtures.

I claim:

The ornamental design for a wall plate for lighting fixtures, as shown.

HARRY C. ADAM.
